UNITED STATES PATENT OFFICE.

HENRY AUGUST KRETSCHMER, OF LA GRANGE PARK, ILLINOIS.

DESIGN FOR A COMBINATION CONTAINER AND PICTURE FRAME.

Application filed January 3, 1928. Serial No. 24,726. Term of patent 14 years.

To all whom it may concern:

Be it known that I, HENRY AUGUST KRETSCHMER, a citizen of the United States, residing at La Grange Park, in the county of Cook and State of Illinois, have invented a new, original, and ornamental Design for Combination Containers and Picture Frames, of which the following is a specification, reference being had to the accompanying drawing, forming part thereof.

The figure is a perspective view of a combination container and picture frame, showing my design.

I claim:

The ornamental design for a combination container and picture frame, as shown.

HENRY AUGUST KRETSCHMER.
